ADJUSTABLE MEANS FOR CHANGING THE
CONTOUR OF SEAT BACK RESTS

Robert E. Lingenfelter, Hereford, Tex.

Application July 1, 1949, Serial No. 102,689

7 Claims. (Cl. 155—162)

1

This invention relates to an adjustable seat, and more particularly to an adjustable back for automobile seats and the like.

It is an object of this invention to provide an adjustable seat back of the kind to be more particularly described hereinafter having vertical and horizontal adjustments to properly suit the particular requirements of any individual using the seat.

Another object of this invention is to provide an adjustable seat back for upholstered seats having provision for adjusting and varying the contour of the seat back for properly supporting the back of a person, the back of the seat being adjustable to particularly suit the contour of the spinal column of the person using the chair, and the adjusting means being retractable within the seat back for disengagement therefrom when and as desired.

Still another object of this invention is to provide an adjustable seat back of this kind which is particularly adapted for use on the backs of seats of automobiles and general upholstered articles of furniture having a substantially vertically-extending upholstered seat back or portion.

With the above and other objects in view, my invention consists in the arrangement, combination and details of construction disclosed in the drawings and specification, and then more particularly pointed out in the appended claims.

In the drawings:

Figure 1 is a side elevation, partly broken away and partly in section, of an upholstered chair having an adjustable seat back constructed according to an embodiment of this invention;

Figure 2 is a transverse section taken on the line 2—2 of Figure 1;

Figure 3 is a fragmentary detail section taken on the line 3—3 of Figure 1, showing the locking means for the adjusting handles of the chair;

Figure 4 is a fragmentary detail section taken on the line 4—4 of Figure 1;

Figure 5 is a fragmentary detail section taken on the line 5—5 of Figure 2, showing the structure of the resilient telescopic connecting link of the horizontal adjusting means for the back member.

Referring to the drawings, the numeral 10 designates generally an upholstered chair having an adjustable back constructed according to an embodiment of this invention. While in the drawings, the chair 10 is represented as an upholstered article of furniture, it is to be understood that other articles of furniture, as the seats in automobiles, buses, trains and the like, may be formed

2

with an adjustable back portion formed according to an embodiment of this invention.

The chair 10 shown in the drawings is formed with a seat portion 11 and a back portion 12 fixedly connected to the rear end of the seat portion, the back 12 and seat 11 being formed with a basic frame 14 having an outer upholstered covering 15 on the forward side thereof. The upholstery or outer covering 15, while shown in the drawings as being continuous over the front side of the back section 12 and the top side of the seat section 11, may be formed in two separate sections, wherein the back portion 12 is formed with a separate covering and the seat portion 11 is formed with its own separate covering.

The chair 10 is formed with a horizontal seat frame 16 having a pair of longitudinally-extending frame members 17 and 18 on the opposite sides thereof which are fixedly connected at their respective ends to the vertically-extending frame members 19 at the forward end of the seat portion 11 and to the vertically-extending frame members 20 at the rear end thereof.

The rear seat frame member 20 is extended vertically upwardly to define the vertically-extending rear frame members for the back 12, and a pair of transversely-spaced-apart, vertically-extending front frame members 21 are connected at their lower ends to the horizontally-extending seat frame members 17 extending upwardly therefrom in forwardly-spaced relation to the rear frame members 20.

The rear frame members 20 and 21 define a rear frame 22 fixedly connected to the rear end of the seat frame 16.

A pair of vertically-spaced-apart, longitudinally-extending, horizontal channels or rail members 24 and 25 are fixedly supported between the vertically-extending frame members 20 and 21 of the back frame 22 on the opposite sides thereof. The channels or rails 24 and 25 define the horizontally-extending guide means for the adjustable member to be more particularly described hereinafter.

A horizontally-adjustable carriage 26 is slidably engaged on the guide means 24 and 25 for horizontal adjustment and includes a pair of vertically-extending side arms 27 and 28. The vertically-extending carriage members 27 and 28 are horizontally spaced apart and connected together by longitudinally-extending connecting members 29 at the upper and lower ends thereof. Rollers 30 are rotatably carried by the extreme outer ends of the side carriage members 28 and

29 for rotatable engagement in the guide means 24 and 25 for slidably supporting the carriage in the back frame 22.

A back member 31 is slidably supported in the carriage 26 for vertical sliding adjustment therein and includes a transverse member 32 which is supported transversely of the back frame 22 between the carriages 26 on the opposite sides of the back 12. A pair of rollers 34 are rotatably carried on the upper end of each side of the cushion or back member 31 and a second pair of horizontally-spaced-apart rollers 35 are rotatably carried on the lower end of each side of the back member, as clearly shown in Figures 1 and 2 of the drawings.

The horizontally-slidable carriage 26 constitutes a vertical guide means for the back member 31, the rollers 34 and 35 slidably or rotatably engaging the guide rails 27 and 28 to provide for the vertical adjustment of the cushion or back member 31 in its selected horizontal position, as defined by the horizontal position of the guide means or carriage 26 in the longitudinally-extending guide means or rails 24 and 25.

A transverse shaft 36 is rotatably supported between the forward ends of the upper seat frame members 17, extending transversely of the seat 11, as clearly noted in Figure 2 of the drawings. A depending crank arm 37 is fixedly connected to one end of the shaft 36 extending downwardly therefrom in the normal position of the shaft 36 and adjustment of the back member 31. A bell crank 38 is rockably supported on the rear end of the frame member 17 and includes a vertically-extending lever arm 39 and a horizontally-extending lever arm 40. The lower end of the vertically-extending lever arm 39 is connected to the depending lever arm 37 by a horizontally-extending connecting link 41. A vertically-extending connecting link 42 is pivoted at its lower end to the rear end of the horizontal lever arm 40 and at its upper end to a pivot pin 44 fixedly carried by the back member 31 intermediate the vertical height thereof. The lever 37 and the bell crank 38, connected to the back member 31 by the links 41 and 42, define the adjusting means for adjusting the back member 31 vertically in the vertical guide member 26 defined above.

A second transverse shaft 45 is rotatably supported on the longitudinal frame members 17 rearwardly of the transverse shaft 36 and an upstanding lever arm 46 is fixed on the shaft 45 at one end thereof. A bell crank or lever 47 is pivotally connected intermediate the length thereof on a supporting pivot bracket 48 which is fixedly supported on the vertically-extending frame member 20. The bell crank or lever 47 includes a depending lever arm 49 and an upstanding lever arm 50 above the pivot pin 51 rotatably carried by the bracket 48. A connecting link 52 is pivoted at one end on the upper end of the lever arm 46 and at its rear end on the lower end of the lever arm 49.

An expandable telescopic link 54 is pivotally connected between the upper end of the lever arm 50 and the rear side of the back member 31. The telescopic member 54 is formed with a tubular link section 55 pivotally mounted at one end on a supporting bracket 56 and an inner bar or rod 57 which is telescopically slidable in the sleeve 55 and spring-pressed outwardly therefrom by a resilient coil spring 58 engaging within the sleeve 55 and pressing the member 51 outwardly

or rearwardly through the open end of the link member 55. The bracket 56 is fixedly secured to the rear side of the back member 31 by suitable bolts 59 or other suitable fastening devices, and the rear end of the shaft or link section 57 is pivotally connected to the upper end of the lever arm 50 by a suitable pivot pin 60. The expandable telescopic link 54 is provided for limited telescopic movement of the link sections 55 and 57, and upon rocking of the lever 46 the back section 31 may be adjusted along the length of the longitudinally-extending guide members 24 and 25. Any undue force or load in excess of the tension of the spring 58 will effect the resilient rearward movement of the back section 31 against the tension of the spring.

A pair of handles 61 and 62 are slidably connected to the outer ends of the shafts 36 and 45 and provide for the manual rocking movement of the shafts and the adjustment of the back member 31. Each of the handle members 61 and 62 is formed with an elongated front hand-gripping section 64 formed with a transverse bore 65 at one end thereof. A rectangular recess 66 is formed at one end of the bore 65, and the outer end of the shaft 36 is slidably connected to the handle section 64 in the recess 66.

A rectangular end element 67 is fixed on the outer end of the shaft 36 and is slidably engageable in the recess 66 and provides a driving connection between the handle section 64 and the shaft 36. A boss 68 is fixed to or formed integral with one side of the handle section 64 in alignment with the bore 65 and the shaft 36 is rotatably engaged through the boss 68, as clearly shown in Figure 3 of the drawings. A resilient coil spring 69 is engaged about the outer end of the shaft 36 between the inner surface of the boss 68 and the inner surface of the end member 67 for constantly biasing the handle 61 inwardly along the length of the shaft 36. A clutch element 70 is fixedly supported on the longitudinally-extending frame member 17 about the shaft 36 on the outer side of the seat 11. The boss 68 carried by the handle 61 is formed with a corresponding interengaging clutch element 71 formed with a plurality of circumferentially-spaced-apart teeth for engagement with the teeth of the clutch element 70 for locking the handle 61 in shaft 36 against rotation in a selected adjusted position of the back member 31.

In the use and operation of the adjustable seat back formed according to an embodiment of this invention, rocking of the handle 61 will provide for the vertical sliding movement of the back member 31 in the carriage or guide member 26, thereby providing the vertical adjustment of the back member. The longitudinal or horizontal adjustment of the back member 31 is accomplished by rocking the handle 62 forwardly or rearwardly at which time the carriage or vertical guide member 26 is adjustably moved along the longitudinal guide members 24 and 25. In this manner the back member 31 will be adjusted vertically and longitudinally of the seat back frame, whereby the contour of the cover 15 may be adjusted to suit the contour of the spinal column of a person using the seat. If it is desired that the adjusting member 31 be not used, the adjusting member may be fully retracted within the seat frame 14 and the front portion of the back cover 15 will be disposed in a substantially conventional manner.

76 I do not mean to confine myself to the exact

details of construction herein disclosed, but claim all variations falling within the purview of the appended claims.

I claim:

1. An adjustable seat back for an upholstered seat having a covered seat frame and a covered back frame, comprising a horizontal guide means carried by said back frame, vertical guide means slidably engaging said horizontal guide means, a covering-engaging member slidable on said vertical guide means and engageable with the back frame cover for varying the contour thereof, and manually-operated means carried by said seat and back frames for vertically and horizontally adjusting said covering-engaging member.

2. In a chair having a back, horizontal guide means carried by said back, vertical guide means slidable on said horizontal guide means, a back member slidably carried by said vertical guide means, a pair of handles pivoted on said chair, connecting means between one of said handles and said back member for adjustably sliding said back member vertically, and connecting means between the other of said handles and said back member for adjustably sliding said back member horizontally.

3. In a chair having a back, horizontal guide means carried by said back, vertical guide means slidable on said horizontal guide means, a back member slidably carried by said vertical guide means, a pair of handles pivoted on said chair, connecting means between one of said handles and said back member for adjustably sliding said back member vertically, and connecting means including a resilient connecting link between the other of said handles and said back member for adjustably sliding said back member horizontally.

4. In a chair having a back, horizontal guide means carried by said back, vertical guide means slidable on said horizontal guide means, a back member slidably carried by said vertical guide means, a pair of handles pivoted on said chair, connecting means between one of said handles and said back member for adjustably sliding said back member vertically, connecting means including a resilient connecting link between the

other of said handles and said back member for adjustably sliding said back member horizontally, and releasable interengaging locking means carried by each of said handles and said chair for releasably securing said handles and said back member in selected adjusted positions.

5. In a chair having a back frame, an adjustable back member slidably supported in said frame for vertical and horizontal sliding movement, adjusting means carried by said chair engaging said back member for sliding said member horizontally, and adjusting means carried by said chair and engaging said member for sliding said member vertically.

15 6. In a chair having a back frame with a flexible cover, an adjustable back member engaging said cover and slidably supported in said frame for vertical and horizontal sliding movement, adjusting means carried by said chair and engaging said back member for sliding said member horizontally, and adjusting means carried by said chair and engaging said member for sliding said member vertically.

25 7. In a chair having a back frame with a flexible cover, an adjustable back member engaging said cover and slidably supported in said frame for vertical and horizontal sliding movement, adjusting means including a resilient telescopic link carried by said chair and engaging said back member for sliding said member horizontally, and adjusting means carried by said chair and engaging said member for sliding said member vertically.

35 ROBERT E. LINGENFELTER.
